UNITED STATES PATENT OFFICE.

WALTER RICHMOND, OF CHICAGO, ILLINOIS, ASSIGNOR TO JOHN ELLIOTT JENKINS,
OF CHICAGO, ILLINOIS.

ELECTRIC SWITCH MECHANISM.

1,419,898.

Specification of Letters Patent. Patented June 13, 1922.

Original application filed October 24, 1911, Serial No. 656,430. Divided and this application filed March 17, 1917. Serial No. 155,424.

To all whom it may concern:

Be it known that I, WALTER RICHMOND, a citizen of the United States, and residing at Chicago, in the county of Cook and State 5 of Illinois, have invented certain new and useful Improvements in Electric Switch Mechanism, of which the following is a specification.

My invention relates to electric switch 10 mechanism which is especially adapted for use in automatically controlled systems, such as those which are thermostatically regulated.

This application is a division of my ap- 15 plication Serial No. 656,430, filed October 24, 1911.

It is an object of this invention to provide an electro-magnetic switch which can never assume a neutral position, and which can- 20 not therefore become inoperative, requiring manual adjustment and correction.

It is another object of the invention to provide an electro-magnetic switch with a blow-out magnet, the energizing current of 25 which will only be instantaneously utilized when the switch is shifted and which will pass through the arc at the switch, and to provide a switch of this character electro- 30 magnetic operating coils equipped with a magnetic sheath to concentrate the force of the magnet.

It is a further object of my invention to provide a controller which may be operated by a thermostat or the like, which is adapt- 35 ed to selectively control switch operating currents, and so associate the switch there- with that the circuit through the controller is opened after the same has made its switch operating contact so that there 40 can be no spark at the controller contact when the same is subsequently moved away from the associated contact, a result ex- tremely desirable in delicate apparatus; and to provide the combination of a primary con- 45 troller (such as a thermostat,) a controller, a switch and an electric element in which the primary controller operating through the controller and switch controls the element but in which no current passes through any 50 part of the apparatus when the electric element is dead.

Figure 1 is a partly diagrammatical view of an electric switch and controller mechanism embodying my invention, the energiz-

ing solenoid magnet being shown in section; 55 and

Figure 2 is a detail view showing the manner of connecting the magnet core to the switch blade.

I have illustrated my electric switch mech- 60 anism in connection with a system of electric heaters 1, 2, for purposes of illustration, al- though it is useful in other applications, as will be evident to engineers. The actuating magnet is of the solenoid type, having two 65 energizing coils 4, 5, which are adapted to move the core 6, in alternate directions to bring the switch blade 8 into engagement with the spring switch contacts 9, 9', or 10, 10'. Instead of securing the stem 12 of the 70 switch blade rigidly to the core, I form the stem into a yoke frame 14 which surrounds the core so that the core may have a free initial movement within the yoke in both directions, striking the latter a hammer blow 75 to ensure a sudden movement of the switch blade from one pair of spring contacts to the other pair.

It is important when operating upon high voltage direct current, such as lighting cir- 80 cuits, that the arc which follows the switch blade should be extinguished. One of the important features of my invention resides in the provision for blowing out the arc 85 after the movement of the switch blade in either direction. The spring contacts 9, 9', are located adjacent the coil 5, and within the influence of the magnetic field of said coil, whereby when the blade 8 is moved from the contacts 9, 9', due to the pull of 90 the coil 5 upon the core 6 the arc which follows the blade will be blown out by the field of the coil 5. In order to extinguish the arc which follows the blade when it is moving away from the contacts 10, 10', I 95 provide a blow out magnet 16, which is connected in shunt to the coil 4, and in the modification of the invention disclosed, is located so that its magnetic field will be strongest opposite the upper portion of the 100 contacts 9, 10, between which the arc is strongest. The part 16^a of Figure 1 is the iron or magnetic core of the blowout magnet 16 and is so arranged as to lead the lines of force where they will be most effective in 105 blowing out the arc which occurs between contacts 10 and 9. The blow-out magnet 16, together with its magnetic core 16^a, is effec-

tively placed to extinguish the arc between the contacts 10 and 9, there being no arc between contacts 10 and 10' or between 10' and 9' because contacts 10' and 9' are electrically connected by a wire as shown.

It is to be particularly noted that when the switch is moving over from the contacts 10, 10', to contacts 9, 9', the energizing circuit for the blow out magnet 16 will pass from the upper contact 10 through the arc to the contact 9, through the switch blade 8 to the contact 9', and back to the pole 35^a, so that the energizing current for the blow out magnet is established through the arc blown out by the magnet at the time the circuit is broken.

The core 6 is somewhat longer than either of the energizing coils, so as to extend into both coils in any position to ensure the starting movement. I also provide an exterior magnetic sheath 18, for the purpose of concentrating, and strengthening the magnetic field and thereby increasing the pull upon the core.

I have illustrated my electric switch mechanism in connection with a thermostatic controlling switch having a switch arm 20 carrying a contact 22, adapted to engage contacts 23 and 24 alternately. The arm is normally restrained by the spring 28, the tension of which can be changed by swinging the arm 29 into dotted line position. The switch arm 20 is moved against the spring tension by means of a fluid expansion thermostat having a thermal tube 30 and an expansion box 31, one face of which consists of a diaphragm and carries the anvil 32 which bears against the switch arm.

The current is brought in from the supply leads through the connection socket 35. With the parts in the position shown, the current enters at the socket contact 35^a, and passes by way of the relay spring contact 10', through switch blade 8, spring contact 10, and conductor 38 to the heater coils 1, 2, or other translating devices, and returns to the other socket contact 35^b by way of the conductor 39. When the circuit connections of the relay or electro-magnetic switch mechanism, are changed by the movement of the thermostatic switch arm 20, causing the contact 22 to engage the contact 24, a circuit will be established through the coil 4. Thereupon the core 6 will be drawn over into the coil 4, causing the blade 8 to move from the contacts 10, 10', into engagement with the contacts 9, 9', thereby breaking the circuit of the translating devices 1, 2. As the switch blade leaves the contact 10, the arc which follows will tend to maintain the circuit across the gap between the contacts 9, 10, and by way of the blade 8, contact 9' to the connection with the socket contact 35^a. This arc, however, will be extinguished

by the magnetic field of the blow out magnet 16, the pole 16^a of which is adjacent to the gap. When the arc is extinguished the circuit will be broken through the coil 4, blow out magnet 16 in shunt thereto, and the heaters 1, 2, and current will not flow through any part of the apparatus until the thermostatic switch arm 20 again establishes the circuit through the coil 5, by way of the contacts 22 and 23. In order that a circuit may be established through one relay coil or the other in all positions of the blade 8, I make the latter of a greater width than the gap between the opposite pairs of spring contacts, as indicated by the intermediate position of the blade shown in dotted lines.

It is to be noted that the circuit through the contacts 23 and 24 is opened immediately after the contact is made, so that upon the next operation by the thermostatic device, the contact 22 leaves a dead contact point, preventing sparking in the delicate portion of the apparatus. In other words, the contact 22 never breaks but only makes the circuit.

An extremely powerful magnet in the smallest possible space can be used in this switch because the magnet is only in circuit a fraction of a second and the heavy current employed is broken in the arc which it blows out. It will thus be seen that the actual design of this blow-out magnet can be varied between extremely wide limits and gives the designer the privilege of placing the blow-out magnet from a mechanical point of view without being strictly confined to electrical necessity.

Having now described my invention, I claim:

1. An electro-magnetic switch having a plurality of sets of contacts, a switch blade adapted to contact with one set or another of said contacts, a magnetic core connected to said blade, a plurality of energizing coils operatively related to said core, one set of contacts being located within the magnetic influence of the adjacent coil, and a blow out magnet having its magnetic field embracing the other set of contacts, and arranged in a circuit including the arc at the adjacent contacts.

2. An electro-magnetic switch having a plurality of sets of contacts, a switch blade adapted to contact with one set or another of said contacts, a magnetic core connected to said blade, a plurality of energizing coils operatively related to said core, one set of contacts being located within the magnetic influence of the adjacent coil, and a blow out magnet having its magnetic field embracing the other set of contacts and being connected in shunt to the distant coil.

3. An electro-magnetic switch comprising two sets of spaced contacts, a switch blade

adapted to contact with either set, and arranged and constructed to maintain contact with one set until after contact with the other set has been established, a pair of coils 5 associated with said switch blade, and adapted to move the latter in opposite directions, a blow out magnet on a shunt circuit from one of said coils, said circuit passing through the switch blade, whereby the energizing circuit 10 of the blow out magnet will pass through the arc to be blown out.

4. In apparatus of the class described, two sets of spaced electric contacts, a switch blade adapted to contact with either or both sets, coils 15 associated with said switch blades for shift-

ing the latter in opposite directions, the circuit for one of said coils being broken upon shifting said blade, a blow out magnet in shunt from said coil, and means for permitting the circuit through the blow out magnet 20 to be maintained through the arc caused by shifting said switch.

In witness whereof, I hereunto subscribe my name to this specification in the presence of two witnesses.

WALTER RICHMOND.
